UNITED STATES PATENT OFFICE.

JULIA STANDISH ALEXANDER, OF HIBRIDGE, NEW YORK.

DESIGN FOR A SUN-DIAL.

46,390.

Specification for Design.

Patented Sept. 15, 1914.

Application filed July 20, 1914. Serial No. 852,068. Term of patent 7 years.

To all whom it may concern:

Be it known that I, JULIA STANDISH ALEXANDER, a citizen of the United States, residing at Highbridge, in the county of the Bronx and State of New York, have invented a new, original, and ornamental Design for a Sun-Dial, of which the following is a specification, reference being had to the accompanying drawing, forming part thereof.

The figure is a plan view of a sun-dial, showing my new design.

I claim:

The ornamental design for a sun-dial, as shown.

JULIA STANDISH ALEXANDER.

Witnesses:

WM. H. ALEXANDER,
EDWARD H. BENEDICT.
